UNITED STATES PATENT OFFICE.

GEORGE C. SAWYER, OF CANTON, NEW YORK.

FAUCET.

SPECIFICATION forming part of Letters Patent No. 427,191, dated May 6, 1890.

Application filed January 8, 1890. Serial No. 336,267. (No model.)

To all whom it may concern:

Be it known that I, GEORGE C. SAWYER, a citizen of the United States, residing at Canton, in the county of St. Lawrence and State 5 of New York, have invented a new and useful Faucet, of which the following is a specification.

This invention relates to faucets of that class more particularly where a stationary 10 casing contains a double conical barrel having a longitudinal perforation opening through its side near the front or upper end and adapted to register with a spout in the casing; and the invention consists of the specific 15 means hereinafter described for maintaining close contact of said barrel with the interior of the casing at all times and automatically taking up the wear thereof.

In the accompanying drawings, Figure 1 is 20 a longitudinal vertical section of my improved faucet. Fig. 2 is a detached side elevation of the barrel. Fig. 3 is a perspective view of the adjustable ring portion of said barrel.

25 The letter C designates the inner (or in the present case the lower) portion of the "casing," which at its lower end is adapted to be screwed into or in other manner connected with the receptacle or pipe from which the liquid is to 30 be drawn, and at its upper end at c this portion is flared, its extreme end having a tubular ring R, provided with a screw-thread on its inner face and a shoulder r at the base of the screw-thread and above the flared portion c.

35 The letter C' designates the outer (or in the present case the upper) portion of this casing, whose body is flared downwardly throughout its length and at its lower extremity has a 40 tubular ring R', provided with a screw-thread on its outer face adapted to fit the thread on the ring R, the lower edge of this ring preferably abutting against or resting on the shoulder r when the parts are assembled. Above 45 this ring R' the portion C' is provided with an annular flange fitting over the upper edge of the ring R and making a close contact therewith, which flange is preferably of the shape shown in Fig. 1, although it may be 50 entirely omitted, if desired. The upper end of the portion C' is provided with a cap or head-piece c', having a small central aperture, and the side of the casing at a suitable

point carries a spout S, communicating with the interior of the casing.

55 The barrel E of my improved faucet consists of a tubular shank E', the upper half E of whose body is conical in shape and adapted to fit snugly within the upper half C' of the casing, and continued upwardly from the 60 end of this conical portion is the shaft A, which passes through the aperture in the head c' and carries the handle B at its outer end for operating the barrel, as will be clearly understood. The tubular passage P through 65 this barrel is closed at the upper end of the latter and near that point opens at X through the side of the barrel at a point adapted to register with the spout S when the barrel is turned to the proper position, and it will be 70 seen that a continuous passage will thus be formed from the receptacle or supply-pipe through the shank E', through the opening X, and out the spout S. The lower portion of this barrel is cylindrical, as shown at E', 75 and between said cylindrical portion and the conical portion E a shoulder e is formed.

Upon the cylindrical portion E' of the barrel slides the ring portion D thereof. This ring is 80 of such an interior tubular diameter as to closely fit the exterior of said shank, and its outer face is flared upwardly, so as to give it a conical form, whereby it will closely fit within the flaring portion c of the casing, as shown in Fig. 1. The ring D when placed upon the 85 shank is normally pressed away from the upper portion E of the barrel by a coiled expansive spring H, surrounding the shank E', with its ends pressing against the shoulder e and against the upper flat end of the ring. 90

The several members of my improved faucet are assembled as follows: The ring D is first placed within the flaring portion c, and its upper flat end will be about on a level with the shoulder r of the lower half C of the 95 casing. The upper portion of the barrel is then seated in the upper portion of the casing, from which it can be removed at any time by unscrewing the handle B from the shaft A or in any other manner disconnecting 100 it therefrom, as will be clearly understood. When the upper portion E is so seated, an opening O will be left above its upper end and below the end piece c'. The two parts of the casing are then brought together and the 105 threads of their respective rings R R' are en-

gaged with each other until the lower edge of the upper ring is drawn firmly against and seated upon the shoulder *r*, when the spring *H* will be to a considerable extent compressed.

5 The barrel can now be oscillated by means of the handle *B* to open and close the faucet, as is obvious, and in such oscillation the shank *E'* will turn in the ring *D*, or else the ring will turn in the flared portion *c*, or both, according as the roughness or smoothness of the respective sliding faces may cause greater or less friction between them; but the outer surface of the upper cylindrical portion *E* must of course slide in contact with the inner face 10 of the upper portion *C'* of the casing. Said upper portion *E* of the barrel is of considerable length, so that the faucet may be used for years without any appreciable wear upon such upper portion; but as the wear thereon 15 takes place the spring *H* will gradually push the barrel upward and the space *O* will be gradually reduced in size until the upper end of the portion *E* strikes the top *c'* of the casing. If the faucet is not by that time worn 20 out, the barrel can be removed and the upper end of the portion *E'* filed off; but I find that this is hardly ever necessary. The ring *D* is comparatively short, being only about half the length of the upper portion *E*, and the 25 expansive pressure of the coiled spring *H*, added to the weight of the parts, will tend more to force the ring *D* downward than it will to force the other part of the barrel upward, the weight of the entire barrel and 30 the continual turning of the barrel, either within the ring *D* or with the ring *D* within the flared portion *c*, all serve in exerting a combined force from their very natures to press this ring *D* downward. When the ring 35 *D* becomes worn, if that wear is upon its outer face it slips downwardly within the flared portion of the casing and exerts the same downward pressure thereon as it did before. If the ring *D* becomes destroyed by long use, 40 it can of course easily be replaced by a new ring. The liquid entering from the source of supply passes through the casing *C* and into the bore *P* of the barrel to its upper end. If the barrel be turned so that the opening *X* 45 registers with the spout *S*, the liquid will flow out of the spout; otherwise the inner face of the upper portion of the casing will cover the opening *X* and the liquid will find no exit. What liquid there is that finds its way 50 around the lower end of the tubular shank *E'* and seeks an exit through the coupled point of the two portions of the casing will be checked by the ring *D*, which is pressed normally by the spring *H* into its wedge-shaped seat, as above described, and what 55 liquid seeks exit through improper channels around the opening *X* will be prevented from such escape by the upper portion *E* of the barrel being pressed closely to its seat within 60 the upper portion of the casing. My improved faucet, if properly made, will therefore not leak at any point, and I may dis-

70 pense with any soft washer or packing at the point of connection between the upper and lower portions of the casing or around the shank *A* at the end of the faucet, which features are so objectionable in the construction of faucets.

75 It is thought that the advantages of my faucet will be obvious, and a further recitation of them is therefore omitted.

Having described my invention, what I claim is—

1. In a faucet, the combination, with the casing having upper and lower portions adapted to be connected at their meeting ends and tapering outwardly therefrom, of the removable barrel comprising two conical portions adapted to fit, respectively, within the two portions of the casing and having a central bore with a branch adapted to register with the lateral spout in the upper portion of the casing, and a spring for keeping said conical portions of the barrel normally distended, substantially as described.

80 90 95 100 105 110 115 120 125

2. In a faucet, the combination, with the casing having upper and lower portions adapted to be connected at their meeting ends and tapering outwardly therefrom, of the barrel, the same comprising the conical portion *E* and the integral tubular shank *E'*, both having the longitudinal bore *P*, opening at *X* at a point opposite the spout *S*, the ring *D*, sliding upon said shank and tapering downwardly, so as to fit the lower portion of the casing, and the spring *H*, surrounding said shank and exerting an expansive force between the upper end of the ring and the lower end of the head *E*, substantially as described.

110 115 120 125

3. In a faucet, the combination, with the casing comprising the long tapered upper portion *C'* and the cylindrical lower portion *C*, provided with a short flaring upper end *c*, said portions being connected by screw-threaded rings and the upper portion carrying a spout *S*, of the barrel, the same comprising the conical head *E*, of such a size as to leave an opening *O* between its upper end and the upper end of the faucet, a tubular shank *E'*, integral with and extending downwardly from the lower end of said head, a shoulder *e* being formed around said lower end, a shaft *A* and handle *B*, connected at the upper end of said head for operating the barrel, a ring *D*, comparatively shorter in length than the head *E* and having a central bore fitting the exterior of the shank *E'*, the outer face of said ring being tapered, so as to fit said flaring portion *c*, and the spring *H*, coiled around said shank and exerting a distending force upon the shoulder *e* and the upper end of the ring, as and for the purpose set forth.

In testimony that I claim the foregoing as my own I have hereto affixed my signature in presence of two witnesses.

GEORGE C. SAWYER.
